(57) **CLAIM**

The ornamental design for a security lever handle assembly, as shown and described.

DESCRIPTION

FIG. 1 is a front perspective view of a security lever handle assembly in accordance with the present invention;

FIG. 2 is a side view thereof;

FIG. 3 is a top plan view thereof;

FIG. 4 is a bottom plan view thereof;

FIG. 5 is a front perspective view thereof shown in an open position;

FIG. 6 is a side view thereof;

FIG. 7 is a top plan view thereof; and,

FIG. 8 is a bottom plan view thereof.

The broken lines shown represent unclaimed subject matter and form no part of the claimed design.
